(57) **CLAIM**

The ornamental design for a tee caddie, as shown and described.

DESCRIPTION

FIG. 1 is a top perspective view of a tee caddie showing my new design;

FIG. 2, is a right side elevational view thereof, where the left side elevational view is a mirror image thereof;

FIG. 3 is a front view thereof;

FIG. 4 is a rear view thereof;

FIG. 5 is a top view thereof; and,

FIG. 6 is a bottom view thereof.

The ornamental design which is claimed is shown in solid lines in the drawings. Any broken lines in the drawings are for illustrative purposes only and form no part of the claimed design.
